[57] **CLAIM**

The ornamental design for a support for leaning body, as shown and described.

DESCRIPTION

FIG. 1 is a perspective view of a support for leaning body showing my new design;

FIG. 2 is a front elevation thereof;

FIG. 3 is a left side elevation thereof, the opposite side being a mirror image thereof;

FIG. 4 is a rear elevation thereof;

FIG. 5 is a top plan view thereof; and,

FIG. 6 is a bottom plan view thereof.

The broken lines are for environmental purposes only and form no part of the claimed invention.
